UNITED STATES PATENT OFFICE.

ALVAN B. GOODBAR, OF ST. LOUIS, MISSOURI, ASSIGNOR TO CHARLES TWEEDIE, OF JEFFERSON CITY, MISSOURI.

APPAREL-SHOE-TIP-DRYING RACK.

1,085,601.

Specification of Letters Patent.

Patented Feb. 3, 1914.

Application filed April 23, 1910. Serial No. 557,184.

To all whom it may concern:

Be it known that I, ALVAN B. GOODBAR, a citizen of the United States, and resident of St. Louis, Missouri, have invented certain new and useful Improvements in Apparel-Shoe-Tip-Drying Racks, of which the following is a specification containing a full, clear, and exact description, reference being had to the accompanying drawings, forming 10 a part hereof.

My invention relates to improvements in apparel shoe tip drying racks, the object of my invention being to construct a rack for drying and hardening the adhesive substance applied to the under face of the tip or vamp in box toe shoes by artificial heat so that the operation of lasting, drying and touching-up may be practically continuous.

A further object of my invention is to 20 construct a drying rack of the class described which is provided with an oven having a heater therein of such conformation that only the toes or tips of the shoes may be subjected to the heat, there being guards 25 provided adjacent the oven to prevent the lasted shoes from contacting with the heated portions of the oven.

For the above purposes my invention consists in certain novel features of construction and arrangement of parts as will be hereinafter more fully described, pointed out in the claims and illustrated by the accompanying drawings, in which:

Figure 1 is an elevation of the complete 35 drying rack, a portion of the base section being in section; Fig. 2 is an end elevation of the complete drying rack; Fig. 3 is an enlarged, detail, sectional elevation taken on the line 3—3 of Fig. 1, illustrating shoes 40 in position so that their tips may be dried in the rack; Fig. 4 is an enlarged, detail, sectional elevation taken on the line 4—4 of Fig. 2; and Fig. 5 is an enlarged, detail, sectional elevation taken on the line 5—5 of 45 Fig. 2.

Referring by numerals to the accompanying drawings: 1 designates the corner uprights.

2 designates the bottom frame members. 50 For rigidly connecting the uprights with the bottom members 2 there are the braces 3.

4—4 designate angle irons connecting the bottom members 2 and 5 designates a cen-

trally, perforated plate carried by the angle irons.

Connecting the bottom members 2 about midway between the angle irons 4 and the ends of the members 2 there are the cross bars 6, each of which carries a caster 7, there being similar casters on the members 2.

8 designates a plate upon which the casters travel. At the approximate center of the plate 8 there is a pin 9 having an integral flange 10 which is secured to the plate 8. The pin 9 may properly be termed a centering pin for the reason that when the plate 5 is positioned over the pin as when the rack is in use the whole rack may be turned and the casters prevented from running off the plate 8.

Connecting the uprights or in other words connecting each pair of uprights are the oven end members 11. Connecting the oven ends are the shelves 12 which are preferably constructed of sheet metal and are provided with an integral portion 13 held in a plane some considerable distance above the shelf proper. Each of the shelves is preferably provided with a sheet of heat insulating material 14 extending from the part 13 to 80 the innermost end of the shelf for purposes hereinafter made clear. Connecting each pair of oven end members 11 is a member comprising a top 15 and side walls 16, the top being horizontal and the side walls vertical and preferably formed integral with the top of a single piece of sheet metal. The lower margins of the side walls 16 are preferably turned inwardly at their lower ends thus reinforcing the side walls as well as 85 to present a margin that will not scratch or mar the shoe tips.

17—17 designate diagonally disposed members extended the full length between the oven end members 11, their lower margins being secured to the inner ends of the shelves 12 and their upper margins being secured to the inside faces of the vertical walls 16 adjacent their tops. The members 17 together with the parts 15 and 16 constitute a heating chamber through which a burner 18 is extended the full length of the rack and is preferably located adjacent the lower ends of the members 17.

As shown in Fig. 4 the burner tubes 18 are perforated throughout their length and

at their innermost ends are externally threaded to receive caps such as 19, the caps being held in place by means of the set screws 20 which are inserted through openings formed in the oven end members 11 and threaded to the caps. At their forward ends the tubes 18 project through and beyond the members 11 and are supported by the reinforcing rings 21. Each of the tubes 18 at their outer ends is provided with a mixer or carbureter 22 and a gas supply controlling valve 23 which may be of any ordinary construction and whose detail constructions form no part of my invention. Each of the tubes 18 connects with a supply pipe 24, a branch 25 of which extends over the top of the rack to a point at the approximate center of the rack about over the centering pin 9. The branch 25 is connected, as shown, by a flexible connection 26 with a source of fuel supply. Arranged immediately over the forward end of each tube there is an opening 27 in each of the members 11 through which a match or the like may be inserted for the ignition of the gas issuing from the burner and, arranged for covering each of the openings 27 there is a movable shutter 28.

If gas be used as a heating medium an arrangement of elements substantially like the arrangement just described is necessary and, by reason of the valves 23, it is obvious that the supply of gas to the different heating chambers may be regulated as required to regulate the temperatures of the different ovens.

In carrying out my invention, no matter what heating medium is employed, it will be necessary to provide some form of heat regulating means. In this connection I do not wish to be understood as limiting myself to the exclusive use of gas as a heating medium.

Formed in the diagonally disposed members 17 of the oven are parallel rows of perforations 29 through which the heat from the burner passes from the heating chamber to the oven proper 30.

As shown, the bottom ends of the diagonally disposed members are spaced apart for the admission of atmospheric air for the proper circulation to force the heat from the burners upwardly into the chamber formed by the members 17 and 15, and thence through the openings 29, thence downwardly into the oven proper 30 thence laterally outwardly to atmosphere.

As shown, the heating chambers and ovens are arranged one above the other with some considerable space between each pair of ovens.

For limiting the distance the lasted shoes may be inserted into the ovens there is arranged, adjacent the lower ends of the walls 16, a guard comprising a tube 31 open at

both ends and externally threaded at each of its ends which is inserted through the slots 32 formed in the members 11 and held in place by nuts 33 one on either side of the member 11.

Embracing the tube 31 is a series of heat insulating tubes 34 which are arranged lengthwise of the tube and preferably of greater diametrical dimensions than the tube so they may at all times be free to rotate about the tubes.

For rotating the entire rack I have provided the handles 35 which are secured preferably to the uprights 1.

In the practical operation of the rack for the rapid and economical drying of the adhesive material applied to the under face of the tip or vamp the shoes are lasted without heels and in this incomplete state are placed with their lasts in the oven, that is their toe portions extend into the oven 30, the guard adjacent the mouth of the oven preventing the shoe from contacting with the vertical wall 16 and the diagonally disposed member 17 with the bottom of the shoe resting upon the insulating material 14 covering the shelf 12, the rear end of the lasted shoe being supported by the extension 13 in a position about normal or that is a position of a shoe provided with a heel. This operation of supplying the rack with lasted incomplete shoes is carried on by an operator until one full side of the whole rack is filled, the operator then rotates the entire rack one half a revolution and then commences the filling of the racks of the other side. If the lasting operator commenced filling the first racks at their top then the "toucher-up" may commence to remove the first shoes placed in the oven which are by this time thoroughly dry. In this manner the lasting, drying and touching-up may be made continuous by the use of a rack as described.

To persons familiar with the art of drying the tips or vamps of box toe shoes it is known that when the drying is accomplished by natural heat the last is left in the shoe from twelve to twenty four hours, thus requiring a vast amount of lasts.

By the employment of a rack in which shoes may be dried by artificial heat the shoes need only be lasted say about one hour each and the last may be then used for lasting another shoe.

While I have shown and described a gas burner for heating the oven I do not wish to be understood as limiting myself to the exclusive use of gas as a heating medium for it is obvious that with slight modifications other heating mediums may be employed.

I claim:

1. A rack, for drying shoe tips by artificial heat, comprising an oven having a portion normally open and arranged to receive the tips of the shoes only, a shoe support ad-

jacent and outside the open portion of the oven and means for discharging heated air directly on the tips of the shoes only.

2. A rack, for drying shoe tips by artificial heat, comprising an oven a portion of which is normally open and arranged to receive the tips of the shoes only, a shoe support adjacent and outside the open portion of the oven, means for discharging heated air directly on the tips of the shoes only and means adjacent the open portion of the oven for limiting the distance of insertion of the shoe tips into the oven.

3. A rotatable rack for drying shoe tips by artificial heat, having ovens oppositely arranged relative to each other and means for heating said ovens.

4. A rotatable rack for drying shoe tips by artificial heat, having ovens oppositely arranged relative to each other, burners for heating said ovens and guards arranged adjacent the mouths of said ovens to limit the distance of inserting shoes into the ovens.

5. A rotatable rack for drying shoe tips by artificial heat, having ovens oppositely

arranged relative to each other, burners for heating said ovens, guards arranged adjacent the mouths of said ovens to limit the distance of inserting shoes into the ovens and shelves arranged under the ovens and provided with an upper face having different horizontal planes for supporting the shoes in proper positions in the ovens.

6. A rotatable rack for drying shoe tips by artificial heat, comprising a series of oppositely arranged ovens, shelves for the support of shoes beneath each oven, heating chambers in communication with said ovens, a source of heat supply to said heating chambers, said ovens being partially open to atmosphere, an open-ended tube arranged adjacent each oven and a sectional insulating sleeve embracing said tube.

In testimony whereof, I have signed my name to this specification, in presence of two subscribing witnesses.

ALVAN B. GOODBAR.
